William Edwards' Patent Oct 30th 1846.

The device referred to in these letters patent is that of making part of the same containing a description in the words of the said William Edwards himself of his improvement in tanning dead leather.

This improvement consists in the application of heat to the tanning of dead leather. This is done either by passing a cylinder through a vat filled with York bark water so calculated as to receive wood or other fuel at the end of the cylinder which should be inserted into the vat. The other end of the cylinder forming a right angle should rise above the top of the vat to conduct the steam from the fire. Heat may also be applied by steam by setting a wooden vat upon a boiler connecting them together and in various other methods. The effect is to entirely extract the tanning principle from the bark in a short time and with this produce a strong decoction of the bark which applied to the hide warms it when going upon the layers, shortens the process and produces a saving of bark and time in the process.
